UNITED STATES PATENT OFFICE

CARL F. CAPELL, OF SANTA MONICA, CALIFORNIA, ASSIGNOR, BY DIRECT AND MESNE ASSIGNMENTS, TO ORNA-METAL AWNING CORPORATION, OF LAS VEGAS, NEVADA, A CORPORATION OF NEVADA

STAPLING MACHINE

Application filed May 29, 1930. Serial No. 457,198.

This invention relates to a stapling machine for hingedly connecting together the panels of metal awnings and the like, and has for its primary object to provide, in a manner as hereinafter set forth, a machine of such glass by means of which such panels may be hingedly connected in a manner to withstand the exertion of a maximum pulling force thereon without separating.

10 A further object of the invention is to provide a machine of the character aforesaid which includes means for forming a length of wire into a staple and inserting the ends thereof through openings in the 15 panels which it is desired to hingedly connect, and further including means for securely anchoring the end portions of the staple with respect to one of the panels.

With the foregoing and other objects in view, the invention consists of the novel construction, combination and arrangement of parts as hereinafter more specifically described, and as illustrated in the accompanying drawings wherein is shown an embodiment of the invention, but it is to be understood that the description and drawings are to be taken as illustrative and that the invention is intended to be limited only by the scope of the claims hereunto appended.

In the accompanying drawings in which like numerals are employed to designate like parts throughout the several views:

Figure 1 is a front elevation of a machine 35 in accordance with this invention.

Figure 2 is a side elevation thereof.

Figure 3 is a rear elevation thereof with the supporting frame shown in section.

Figure 4 is a sectional view through the 40 supporting frame showing the staple affixing mechanism in front elevation.

Figure 5 is a section through the supporting frame showing the hole punching mechanism in rear elevation.

Figure 6 is a sectional detail taken at a

point indicated by the line 6—6 of Figure 3.

Figure 7 is a sectional detail taken at a point indicated by the line 7—7 of Figure 5.

Figure 8 is an enlarged fragmentary sectional elevation of the hole punching mechanism.

Figure 9 is a fragmentary bottom plan of a pair of panels showing one of the staples connecting the same.

Figure 10 is a sectional detail showing the 55 position of a staple when first inserted through the panels to be connected thereby.

Figure 11 is a sectional detail showing the preliminary clinching operation for the end portions of a staple.

Figure 12 is a sectional detail showing the final clinching operation of the end portions of a staple.

Referring to the drawings in detail, the numeral 1 designates generally a horizontally disposed skeleton frame from which is suspended a vertically disposed skeleton frame indicated generally at 2. The frame 1 is provided at the sides thereof with rotatable wheels 3 adapted to ride along a track 4 for supporting the frames 1 and 2. Mounted on the horizontally disposed frame 1 is a hole punching mechanism indicated generally at 5 and a staple affixing mechanism indicated generally at 6.

The hole punching mechanism includes an angle plate 7 which extends transversely of the frame 1 adjacent the forward edge of the latter. Extending in parallel relation to the vertically disposed portion of the angle plate 7, and in spaced relation thereto, is a supporting bar 8 to one end of which is secured a pair of spaced uprights 9. The uprights 9 are disposed on opposite sides of the bar 8 and project above the latter. Having one 80 end pivotally connected to the uprights 9 is a supporting arm 10 for a guide element indicated generally at 11. The guide element 11 projects beyond the free end of the arm 10 and is formed in its projecting end 85

face with a horizontally disposed slot 12. The guide 11 is normally maintained in engagement with the upper face of the bar 8 by means of a tension spring 13, one end of which is secured to the arm 10, and the other end of which is secured to the frame 2.

Carried by the supporting bar 8 is a needle supporting device indicated generally at 14. The needle supporting device 14 includes a pair of spaced uprights 15 which are fixedly secured at their upper ends to the supporting bar 8, and which depend below the latter. The uprights 15 are disposed on opposite sides of the bar 8. Interposed between lower end portions of the uprights 15 is a spacer block 16 which is formed with a pair of vertically disposed openings having threaded walls for engagement with the threads of a pair of adjusting screws 17 which extend through the block 16. Each of the adjusting screws 17 is provided with a lock nut 18 by means of which the adjusting screw may be maintained in proper position with respect to the spacer block. Seated on the upper ends of the screws 17 are a pair of needles 19 which extend through vertically disposed openings 20 in the supporting bar 8. The needles 19 further extend through openings 21 in the guide element 11 when the latter is seated on the supporting bar 8. The needles are formed with tapered upper ends as indicated at 22. Extending through one of the uprights 15 and into the supporting bar 8 are a pair of set screws 23 for engagement with the needles 19 to maintain the latter in seated position with respect to the adjusting screws 17.

Having one end pivotally connected to the uprights 9 adjacent the upper ends of the latter is an arm 24 upon the free end of which is mounted a supporting device for a pair of elongated needle receiving elements 25. The supporting device for the needle receiving elements 25 is indicated generally by the numeral 26. The supporting device 26 is of elongated formation disposed at a right angle to the arm 24 and is formed with vertically disposed openings 27 into which the needle receiving elements 25 slidably extend. The upper end portions of the openings 27 are formed with threaded walls for engagement with the threads of a pair of adjusting screws 28, each of which is provided with a lock nut 29 for maintaining the same in adjusted position. The upper ends of the needle receiving elements 25 are maintained in engagement with the lower ends of the adjusting screws 28 by means of a pair of set screws 30. The needle receiving elements 25 are formed at their lower ends with upwardly tapering recesses 31 for the reception therein of the upper ends of the needles 19.

Having its upper end pivotally connected with the arm 24, intermediate the ends of

the latter, is a link 32, the lower end of which is pivotally connected with a foot treadle 33 pivotally mounted on the frame 2. The arm 24 is normally maintained in an elevated position with respect to its pivotal mounting by means of a tension spring 34, the respective ends of which are connected with the treadle 33 and frame 1. Pivotally connected to the uprights 9, adjacent the lower ends of the latter, is a lever 35 which is arranged with respect to the supporting bar 8 to permit a limited reciprocating movement of the lever beneath the bar. Seated on the free end portion of the lever 35 is a pin 36 which slidably extends through an opening through the bar 8 into engagement with the lower face of the guide element 11. The action of the spring 13 normally causes the guide element 11 to depress the pin 36 whereby the handle 37 of the lever 35 is normally maintained in a raised position as shown in full lines in Figure 5. Upon the actuation of the handle 37 to the position shown in dotted lines in Figure 5, the pin 36 is moved upwardly by the lever 35 whereby the guide element 11 is raised from its seated position on the bar 8 to the position shown in dotted lines in Figure 5. Seated on the upper face of the arm 10 is a spacer block 38 which provides a stop for the arm 24 when the latter is moved downwardly, to prevent the walls of the recesses 31 from coming into contact with the needles 19.

The stapling mechanism includes an angle plate 39 which is mounted on the frame 1 rearwardly of the plate 7 and in parallel, spaced relation thereto. Extending in spaced, parallel relation to the vertically disposed portion of the plate 39 is a supporting bar 40 to one end of which is secured a pair of spaced uprights 41 projecting above the bar 40. The uprights 41 are disposed on opposite sides of the bar 40 with one of such uprights interposed between the bar 40 and the vertically disposed portion of the plate 39. Slidably mounted on the bar 40 is a shuttle bar 42, the upper face of which is in sliding engagement with a spacer plate 43 secured to one of the uprights 41. A forward end portion of the shuttle bar 42 is provided with a side plate 44 which forms a shoulder 45 which is normally maintained in engagement with an edge face of one of the uprights 41 by means of a tension spring 46, the respective ends of which are secured to the side plate 44 and one of the uprights 41. At the outer end thereof, the shuttle bar 42 is provided with a handle member 47 by means of which the shuttle bar may be moved longitudinally against the tension of the spring 46.

Having one end pivotally connected with the bar 40 is a trigger arm 48 which is provided adjacent its free end with an upward

projection 49 for engagement with the walls of a recess 50 formed in the lower face of the shuttle bar 42. The projection 49 is normally maintained in engagement with the lower face of the shuttle bar 42 by means of a tension spring 51, the respective ends of which are secured to the trigger arm 48 and one of the uprights 41. Upon the movement of the shuttle bar 42 against the tension of the spring 46 a sufficient distance to bring the recess 50 into alignment with the projection 49, the latter is drawn into the recess to prevent further movement of the shuttle bar until the projection 49 is released from the walls of the notch 50. The projection 49 may be released from the walls of the notch 50 by means of a lever 52, one end of which is pivotally connected to the supporting bar 40 in spaced relation thereto. The free end of the lever 52 is normally maintained in an elevated position by its frictional engagement with a leaf spring 53 which is supported on a rod 54 extending through the uprights 41 and spacer plate 43. Upon movement of the free end of the lever 52 in a downward direction, the lever is brought into contact with a stop 55 projecting from the trigger arm 48 whereby the free end of the latter is moved downwardly against the tension of the spring 51 to disengage the projection 49 from the walls of the recess 50. Upon the disengagement of the projection 49 from the walls of the recess 50, the tension spring 46 operates to move the shoulder 45 into engagement with an edge face of one of the uprights 41. The lever 52 is provided with a handle member 56 for operating the same.

Projecting laterally from a spacer block 57 secured to the pivoted end portion of the lever 52 is a staple forming element 58 which is disposed over an arcuate recess 59 in the upper face of the bar 40 when the lever 52 is swung about its pivot to its elevated position. Upon a downward movement of the lever about its pivot, the staple forming element 58 is moved to a position within the recess 59. The staple forming element 58 is formed with a rounded lower face corresponding in contour to the wall of the recess 59. Formed in the end of the shuttle bar 42 opposite the handle member 47 is a slot 60 within which is secured one end of a leaf spring 61. The slot 60 is adapted to have inserted therein one end of a length of wire, such as 62, which is held in position within the slot by means of the spring 61. The wire 62 is inserted within the slot 60 with the shuttle bar moved to the position in which the projection 49 engages the wall of the recess 50, and with the lever 52 moved to its elevated position. With the shuttle bar 42 and lever 52 thus positioned, the wire 62 extends across the recess 59 along the upper face of the bar 40, and beneath the staple forming element 58. Upon a downward movement of the lever 52, the lower face of the staple forming element 58 is brought into engagement with the wire 62 whereby the central portion of the latter is forced into the recess 59, assuming the contour of the latter.

Having an end portion disposed between the spacer plate 43 and one of the uprights 41 is an arm 63 which is provided in such end portion with an elongated slot 64 through which the rod 54 loosely extends. Carried by the opposite end of the arm 63 is a hammer element 65 which is fixedly secured to the arm and depends below the latter. A portion of the hammer element 65 adjacent the free end of the arm 63 is formed in its lower face with a convex recess 66. In spaced relation to the recess 66, the hammer element 65 is provided on its lower face with a projection 67. Pivotally connected to the arm 63, between the slot 64 and hammer element 65, is a lever 68, the lower end of which is pivotally connected to a foot treadle 69 which is pivotally mounted on the vertically disposed frame 2. The arm 63 is normally maintained in its elevated position by means of a tension spring 70 the respective ends of which are connected with the treadle 69 and the horizontally disposed frame 1. Connecting the lever 68 with the frame 1 is a tension spring 71 which normally maintains the end wall of the slot 64 farthest from the hammer element 65 in engagement with the rod 54. The lever 68 projects above the arm 63 and is provided at its upper end with a handle member 72 by means of which the lever 68 and arm 63 may be moved against the tension of the spring 71 to bring the end wall of the slot 64 nearest to the hammer element 65 into engagement with the rod 54.

In the operation of the machine, a pair of panels, such as 73 and 74 are fixedly secured in any suitable manner with an edge portion of the panel 73 projecting into the slot 12 in the guide element 11, and with an edge portion of the panel 74 seated on the upper face of the guide element 11 and projecting inwardly from the edge portion of the panel 73 which is disposed within the slot 12. Before the edge portion of the panel 73 is inserted in the slot 12, such edge portion is provided with a series of spaced openings, such as 75. The openings 75 are arranged in spaced relation and at the points at which it is desired to connect the panel 73 with the panel 74. With the panels 73 and 74 thus arranged, the frames 1 and 2 are moved in a forward direction along the track 4. Owing to the tension of the spring 13, the panel 73 will be maintained in engagement with the point 22 of the outermost of the needles 19. The openings 75 in the panel 73 are arranged from

the inner edge of the panel a distance equal to that between the outermost opening 21 through the guide element 11 and the inner end of the slot 12 in order that the openings 75 may be brought into alignment with the outermost of the openings 21 by the movement of the frame 1. When the foremost of the openings 75 is brought into alignment with the outermost opening 21, the upper end 22 of the outermost needle 19 will be inserted through such opening 75 to automatically stop the forward movement of the frame. The foot treadle 33 is then depressed by means of which the needle receiving elements 25 are moved downwardly into engagement with the upper face of the panel 74 causing the points 22 of the needles 19 to be forced through the panel 74 to punch therefrom relatively small openings 76. The foot treadle 33 is then released to permit the arm 24 to be swung upwardly about its pivot by the action of the spring 34, after which the handle 37 of the lever 35 is swung downwardly to move the guide element 11 upwardly for disengaging the upper ends of the needles 19 from the openings 76 in the panel 74. The frame 1 is then moved forwardly to bring the next opening 75 into alignment with the outermost opening 21, after which the above described operation is repeated.

The staple affixing mechanism is so arranged with respect to the hole punching mechanism that when the second opening 35 75 is brought into alignment with the outermost opening 21, the first opening 75 as well as the openings 76 adjacent thereto will be brought over the recess 59 in the supporting bar 40. The shuttle bar 42 is then moved 40 against the tension of the spring 46 to bring the projection 49 of the trigger arm 48 into engagement with the walls of the recess 50 in the lower face of the shuttle bar. A length of wire 62 is then inserted into the slot 60 in the forward end of the shuttle bar as heretofore described, after which the lever 52 is swung about its pivot in a downward direction whereby the length of wire 62 is forced into the recess 59 by the action of the staple forming element 58. As previously described the downward movement of the lever 52 causes the projection 49 to be disengaged from the walls of the recess 50 whereby the shoulder 45 on the shuttle bar is brought into engagement with an edge face of one of the uprights 41 by the action of the spring 46.

After the return of the shuttle bar 42 to its normal position, the arm 63 is moved 60 against the tension of the spring 71 by means of the handle member 72, which brings the recess 66 in the lower face of the hammer element 65 into a position for contact with the end portions of the wire 62 upon swinging the arm 63 downwardly

about its pivot. The arm 63 is then swung downwardly by means of the foot treadle 69 which brings the hammer element 65 into engagement with the upper face of the panel 74 to force the end portions of the wire 62 through the openings 76 punched from the panel 74. Upon the insertion of the end portions of the wire 62 through the openings 76, the convex recess 66 is brought into engagement with the end portions of the wire 75 whereby the end portions of the wire are forced away from each other as illustrated in Figure 11. The foot treadle 69 and handle member 72 are then released to permit the upward movement of the arm 63, and also to permit a longitudinal movement of the arm 63 in a manner to bring the projection 67 of the hammer element 65 into a position for engagement with the end portions of the wire 62 upon a downward movement of the arm 63 about its pivot. The treadle 69 is then again depressed whereby the projection 67 is forced against the end portions of the wire 62 to clinch said end portions as shown in Figure 12. The foot treadle 69 is then released and the frame 1 is again moved forwardly along the track 4 as heretofore described. Upon the forward movement of the frame 1, the wire 62 which has just been formed into a staple connecting the panels 73 and 74 passes through a recess 77 formed in the vertically disposed portion of the angle plate 39.

If desired a guide element 78 may be secured to the angle plate 39 as illustrated in Figure 2. The guide element 78 is of elongated formation and extends in a forward direction from the angle plate 39. Slidably mounted on the guide element 78 is a stop 79 which is adjusted to position the same a distance from the recess 59 equal to the distance between the recess 59 and the openings 21 through the guide element 11. When the guide element 78 is employed, the last formed staple will be brought into engagement with the stop 79 coincidentally with the bringing of the last formed openings 76 into alignment with the recess 59, and with the bringing of another of the openings 75 into alignment with the outermost opening 21 in the guide element 11. When it is desired to again move the frame 1, the guide element 78 is moved in any suitable manner to move the stop 79 out of the path of the staple in engagement therewith to permit the staple 110 to pass the stop 79, after which the guide element 78 is again moved into a position to bring the stop 79 into the path of travel of the last formed staple.

It is thought that the many advantages of a stapling machine in accordance with this invention will be readily apparent, and although the preferred embodiment of the invention is as illustrated and described, yet it is to be understood that changes in the 125

size, shape and arrangement of parts may be resorted to, so long as such changes fall within the scope of the invention as defined in the appended claims.

5 What I claim is:

1. In a stapling machine for hingedly connecting a perforated panel with an imperforate panel, the combination of a frame adapted to be moved with respect to the 10 panels, a punching mechanism carried by the frame for forming openings through the imperforate panel, and a staple affixing mechanism including a staple forming means and acting to extend one side of the 15 formed staple through said panels, the other side of the staple through one of said panels, and to secure to the latter panel the ends of the staple.

2. In a stapling machine for hingedly 20 connecting a perforated panel with an imperforate panel, the combination of a frame adapted to be moved with respect to the panels, a punching mechanism carried by the frame for forming openings through the 25 imperforate panel, and a staple affixing mechanism including a staple forming means and acting to extend one side of the formed staple through said panels, the other 30 side of the staple through one of said panels, and to secure to the latter panel the ends of the staple, said mechanisms being relatively 35 arranged to provide for the extension of a staple through a pair of openings formed in the imperforate panel simultaneously with the forming of another pair of openings in such panel.

3. In a stapling machine for hingedly connecting a perforated panel with an imperforate panel, the combination of a frame 40 adapted to be moved with respect to the panels, a punching mechanism carried by the frame for forming openings through the imperforate panel, and a staple affixing mechanism including a staple forming 45 means and acting to extend one side of the formed staple through said panels, the other side of the staple through one of said panels, and to secure to the latter panel the ends of the staple, said punching mechanism including 50 a pair of spaced needles for engagement with one face of the imperforate panel and further including a pair of needle receiving elements for engagement with the opposite face of the imperforate panel.

55 4. In a stapling machine for hingedly connecting a perforated panel with an imperforate panel, the combination of a frame adapted to be moved with respect to the 60 panels, a punching mechanism carried by the frame for forming openings through the imperforate panel, and a staple affixing mechanism including a staple forming means and acting to extend one side of the 65 formed staple through said panels, the other side of the staple through one of said

panels, and to secure to the latter panel the ends of the staple, said punching mechanism including a pair of spaced needles for engagement with one face of the imperforate panel and further including a pair of needle receiving elements for engagement with the opposite face of the imperforate panel, said needles and needle receiving elements being longitudinally adjustable, said needles having tapered outer end portions. 70

5. In a stapling machine for hingedly connecting a perforated panel with an imperforate panel, the combination of a frame adapted to be moved with respect to the 75 panels, a punching mechanism carried by the frame for forming openings through the imperforate panel, and a staple affixing mechanism including a staple forming means and acting to extend one side of the formed staple through said panels, the other 80 side of the staple through one of said panels, and to secure to the latter panel the ends of the staple, said staple affixing mechanism further including a rigid bar for supporting the formed staple, and a pivotally mounted hammer element for forcing portions of the panels toward said rigid bar. 85

6. In a stapling machine for hingedly connecting a perforated panel with an imperforate panel, the combination of a frame adapted to be moved with respect to the 90 panels, a punching mechanism carried by the frame for forming openings through the imperforate panel, and a staple affixing mechanism including a staple forming 95 means and acting to extend one side of the formed staple through said panels, the other side of the staple through one of said panels, and to secure to the latter panel the ends of the staple, said staple affixing mechanism further including a rigid bar for supporting the formed staple, and a pivotally mounted hammer element for forcing portions of the panels toward said rigid bar, 100 said hammer element having its operating face formed with a convexed recess and further formed with a projection adjacent the recess. 105

7. In a stapling machine for hingedly connecting a perforated panel with an imperforate panel, the combination of a frame adapted to be moved with respect to the 110 panels, a punching mechanism carried by the frame for forming openings through the imperforate panel, and a staple affixing mechanism including a staple forming 115 means and acting to extend one side of the formed staple through said panels, the other side of the staple through one of said panels, and to secure to the latter panel the ends of the staple, said staple affixing mechanism further including a rigid bar for supporting the formed staple, and a pivotally mounted hammer element for forcing portions of the panels toward said rigid bar, 120 125 130

said hammer element having its operating face formed with a convex recess and further formed with a projection adjacent the recess, said hammer element being slidable with respect to its pivot to provide for the positioning of said recess and projection selectively in alignment with the formed staple.

In testimony whereof I affix my signature hereto.

CARL F. CAPELL.
